UNITED STATES PATENT OFFICE

FREDERICK C. LAVARACK, OF MONTCLAIR, NEW JERSEY, ASSIGNEE TO RAILROAD
ACCESSORIES CORPORATION, OF NEW YORK, N. Y., A CORPORATION OF NEW YORK

RELAY RACK

Application filed January 9, 1931. Serial No. 507,557.

This invention relates to railway signalling, especially to railway signal tower fittings, and more particularly to railway signal tower, or other structure, combined relay and terminal racks.

Those acquainted with modern railway signalling, especially modern railway electric signalling, in which free and extensive use is made of track circuit sections, are well aware that the complexity and extent to which modern track circuit signalling has progressed necessitates an immense number of track and control relays assembled under one roof, generally that of the signal tower.

Those acquainted with the volume of present traffic over the railway lines located in and approaching the great railway terminals in the larger cities, and the railway lines extending 40 or 50 miles from the larger cities in some instances, know that the volume of traffic is such that the slightest impediment thereto results, not only in annoying delays both to the railway officials and the passengers, but also, especially in the case of excess fare trains in great financial loss to the railway.

At a place like the Grand Central Terminal in New York city and the tracks forming the approach thereto for a distance of 40 or 50 miles therefrom, excess fare trains are operated in numerous sections with not more than one and one half minutes headway therebetween, so that the slightest delay due to the failure of trackway appliances, is of very serious moment.

Heretofore, large numbers of track relays and control relays have been assembled in signal towers, sometimes made of wood, on relay shelves or supports also constructed of wood. Such construction not only is an extremely dangerous fire hazard, but is also an extreme operating hazard, because, in case of fire, the enclosing structure and the relay supporting structure are soon consumed with the total destruction of the track and control relays, and the consequent entire disruption of the signal service.

The more modern structures utilized as signal towers are now constructed of substantially non-inflammable material, but little or

nothing has been done about constructing the relay supports of non-inflammable material, and practically no thought has been given to constructing relay supports of such a nature that they will not only be non-inflammable 55 but will most efficiently support the relays, to the end that they will be systematically arranged, well presented for inspection, and so positioned as to facilitate the running of the necessary wires thereto with proper support and systematic arrangement for those wires.

A principal object of this invention is the provision of a non-inflammable relay rack.

A further object of this invention is the 65 provision of a relay rack of such construction that it will be adapted for a small assemblage of relays and also for the largest possible assemblage of relays by an expansion substantially consisting in a duplication of units. 70

A further object of this invention is the provision of a relay supporting rack of such construction that all machine work thereon may be done in a shop or factory, and it may then be assembled in the field by comparatively unskilled workmen, by the use of only those kinds of tools which unskilled workmen may well be able to manipulate, such as, wrenches and screw-drivers. 75

A further object of this invention is the 80 provision of a relay rack of the type described which will be of such construction that the relays will be pendant from a vertical surface, thereby obviating the known difficulties arising from resting a relay on a horizontal shelf.

A further object of this invention is the provision of a structure of the type specified which will provide vertical surfaces to which relays may be hung provided with 90 regularly arranged and regularly spaced perforations predeterminedly arranged to provide for the reception of any of the several well known forms of track and control relays now used in railway electric signalling. 95

A further object of the invention is the provision of a relay rack of the type specified which will in addition to providing for the hanging of relays thereon also provide for the attaching thereto of standard terminal 100

blocks and lightning arresters by including therein a vertical surface orificed to receive supporting bolts properly positioned for attaching any of the well known standard forms of terminal blocks or lightning arresters, and also orificed suitably for running the necessary conducting wires thereto.

A further object of the invention is the provision of a relay rack of the type specified which will also include suitable wire runs and wire racks for positioning and supporting the necessary wires connecting with the relays, terminal blocks, and lightning arresters mounted on the relay rack.

Further objects and advantages will appear as the description of the particular physical embodiment selected to illustrate the invention progresses and the novel features will be particularly pointed out in the appended claims.

In describing the invention in detail and the particular physical embodiment selected to illustrate the invention, particular reference is had to the accompanying drawings and the several views thereof, in which like characters of reference refer to like parts throughout the several views, and in which:

Figure 1 is a side elevational view of a relay rack embodying applicant's invention; Fig. 2 is a horizontal sectional plan view on the plane indicated by the line II—II of Fig. 1, viewed in the direction of the arrows at the ends of the line; Fig. 3 is a fragmentary sectional view on the plane indicated by the line III—III of Fig. 2, viewed in the direction of the arrows at the ends of the line; Fig. 4 is a sectional elevational view on the plane indicated by the line IV—IV of Fig. 2, viewed in the direction of the arrows at the ends of the line; Fig. 5 is a horizontal sectional view on the plane indicated by the line V—V of Fig. 4, viewed in the direction of the arrows at the ends of the line; Fig. 6 is a separated or "exploded" view illustrating the connection between a vertical post and a vertical relay supporting member used in my invention; Fig. 7 is a top plan view of a pinnacle used with my invention; Fig. 8 is a sectional view on the plane indicated by the line VIII—VIII of Fig. 1, viewed in the direction of the arrows at the ends of the line.

In order that the relay rack of my invention shall be practically and substantially non-inflammable, I construct the main frame thereof entirely of metal, preferable steel, except such portions thereof which may more readily be cast of iron. I do employ some relatively few parts such as wiring templates and wire supporting hollow rolls formed of an insulating material which is somewhat inflammable, but the proportion of such material is such that the structure as a whole is substantially non-inflammable.

My relay rack, broadly considered, in-

cludes four or more corner posts as 1, 2, 3 and 4, as best shown in Fig. 2, and the two posts 2 and 4 shown in elevation in Fig. 1; lateral braces as 5 and 6, best shown in Fig. 2; a plurality of relay supporting panels as 7 and 8, best shown in Fig. 1; and somewhat similarly formed and supported terminal block panels as 9, best shown in Fig. 4; and a wire supporting rack designated as a whole by 10, best shown in Fig. 2.

The corner posts, as 1, 2, 3 and 4, are formed preferably of angle-iron, each corner post being composed of two angle-irons as 11 and 12, as best shown in the upper left hand corner of Fig. 2. Each leg of each angle is perforated at small intervals forming openings for the reception of the bolts or like fastenings.

The lowest portion or foot of each corner post composed of two angle-irons is inserted in a pedestal, as 13 and 14, best shown in Fig. 1, and shown in plan view in Fig. 8. Each pedestal, as 13, is formed with a T-slot 15 which is of such dimensions as to receive and snugly fit the ends of the two adjoining angle-irons forming the corner. The pedestal 13 is also formed with orifices for the reception of fastening means such as lag screws or bolts, 16 and 17, for bolting the corner post to a suitable foundation. Interposed between the foundation and the pedestal 13, I preferably employ a metal blade, as 18, so as not only to secure a proper bearing, but also to afford a uniform surface for the pedestal 13 to abut and the angle-irons 11 and 12 to rest against.

At the top of each corner post I place a pinnacle as 19 and 20, best shown in Fig. 1. This pinnacle, as shown in Fig. 7, is formed with a T-slot 21 for receiving the two adjacent angle-irons. This pinnacle firmly holds the two angle-irons together and in position, being assisted in this function by the pedestal 13 and through bolts, as 22 and 23, passed at intervals through aligning orifices in abutting legs of the angle-bars, as best shown in Fig. 2.

The corner posts, as 1, 2, 3 and 4, may be of any desired length, but in practice it is preferred to make them of such length that the relays supported by the rack will all be well within the range of reach and vision to one standing upon the same base upon which the rack is positioned. The distance between any two posts longitudinal of the rack, as between posts 2 and 4, is any convenient distance which does not necessitate a relay panel such as 7 being of a length awkward to handle. Applicant has found about five feet and one half as an average convenient length.

The corner posts, as 1 and 2, are separated transversely a distance such that stability will be maintained, and ample space will be provided on the wire racks 10 for the recep-

tion of such wires as may be needed to connect with the various instruments supported by the relay rack. In practice, applicant spaces posts, as 1 and 2, about 18 inches apart, and in order to maintain the spacing and make the structure rigid, lateral braces, as 5, are positioned at intervals between the posts, as 1 and 2. These lateral braces are bolted, as by bolts 25 and 26, to the legs 10 of the angle-bars forming the corner posts. The upper and lower edges of the lateral braces, as 5, are carefully rounded so as to prevent them from abrading the insulation of wire which may be drawn over them longitudinally of the relay rack.

In Fig. 1, applicant has shown two relay panels or supporting braces. The number of these supporting surfaces or panels may be as desired depending upon the height of the 20 corner posts and the spacing of the panels one from the other.

Each panel, as 7, is formed exactly like every other panel, as 8, except that panels, as 7 and 8, which form the terminal panels of 25 one end of the structure are longer than intermediate panels, as 27 and 28. The intermediate panels, as 27 and 28, extend from the center line of a post, as 4, to the center line of another post, whereas the panels, as 30 7 and 8, extend from the center line of a post as 4 to and beyond the center line of a post, as 2, so as to afford a more agreeable appearing finish to the structure.

Each of the panels, as 7, 8, 27, and 28, are 25 all generally channel shaped, as best shown in Fig. 6, with the ends 29 and 30 of the legs of the channel turned over parallel with the face of the channel, as best shown in Fig. 6. The ends of the legs 29 and 30 are each 30 formed with substantially semi-circular cut-out portions, as 31 and 32, of such size that the bolts, as 33 and 34, used for attaching the panels to the corner posts may nicely rest 35 therein to the end that no endwise movement of the panels may take place even if the bolts become slightly loosened. In order to further prevent a panel from actually falling if the bolts should become loosened, a panel clamp as 35, substantially U-shaped in cross-section, is interposed between the head of 40 the bolt, as 33, and the leg, as 29, of the channel, as 7, all as well shown in Fig. 4. The U-shaped panel clamp is formed with orifices, as 36 and 37, through which the bolts, as 33 45 and 34, pass, and the bottom of the U rests against the turned over ends of the legs of the channel. The ends of the U-shaped panel clamp extend from one leg to the other of the panel, and the bolts as 33 and 34 pass through 50 orifices, as 36 and 37, of the U-shaped panel clamp, then fitting into the semi-circular notches, as 31 and 32, pass through leveling plates, as 38 and 39, and through an orifice 55 in one of the legs of the angle-bars forming 60 a corner post. By this method of construc-

tion it is quite impossible for the panel, 7, to become detached from bolts, as 33 and 34, so as to drop, and interfere, not only the relays suspended by it, but perhaps other relays suspended on other relays below it. 70 Such complicated construction as has been devised for supporting the relay panels, as 7, 8, 27, and 28, would in most structures be unnecessary but it must be continually borne in mind that all structures appertaining to railway signalling must possess factors of safety far surpassing ordinary structures so that, although, for ordinary purposes a bolt merely passed through a leg of the panel and into and through an angle-iron would be 75 sufficient, railway signalling structures require the provision of fastening means which must be not only easily manipulated but which, even if loosened so that their proper function is not being properly performed, 80 they will still function to prevent an accident which might result in the giving of false clear signals. Each end of each of the relay panels is supported in the manner described, the abutting ends of two panels and 85 their connecting means being quite clearly shown in Fig. 5, in section.

The number of corner posts on one side of the relay rack, as 2 and 4, may be as desired so that when a suitable number of intermediate corner posts, as 4, are used, the relay supporting structure may be of any desired length to support any desired number of relays. The structure is practically a 95 unit structure comprising four corner posts 100 and relay supporting panels. If a longer structure is desired two additional corner posts are added for each new group of relay supporting panels desired.

The relay panels, as best shown in Fig. 1, 105 have longitudinal slots, as 40 and 41, therein arranged in pairs and supported a distance from each other such that an ordinary relay can be positioned therebetween. Each slot is covered by a wiring template, as 42 and 43. 110 These wiring templates are formed of insulating material and with orifices, as 44 and 45, therein for the reception of insulating 115 conducting wires so that the wires going to a relay may be passed through the orifices, as 44 and 45, and suitably supported and positioned to properly connect with a relay, as 46, which is hung upon the relay panel by means of bolts, as 47 and 48, passed through a portion of the relay structure and through orifices formed in the relay panel at predetermined 120 distances apart. These orifices for receiving the bolts, as 47 and 48, are arranged in pairs at a proper spacing to provide for hanging any of the ordinary and well known 125 standard forms of track or control relays. In Fig. 1 three different pairs are shown, as 49, 50 and 51.

Substantially opposite to the relay panels, 130 as 7, on the faces of the posts, as 1 and 3, on

the back-side of the relay rack are positioned terminal block or lightning arrester panels as 9, best shown in Fig. 4, in section, and in back view in Fig. 3. These terminal block panels are preferably made of substantially the same structural shape as the relay panels, and are attached to the posts, as 1 and 3, in substantially the same manner as the relay panels are attached to the posts 2 and 4. In fact, the terminal block panels 9 are substantially the exact counter parts of the relay panels except that the terminal panels, as 9, have their broad face differently perforated. The terminal panels, as 9, have a plurality of perforations, as 52 and 53, for the reception of attaching bolts, as 54 and 55, for attaching a terminal block, as 56, or a lightning arrester of substantially similar form, to the panel. The panel, as 9, further has orifices, as 57 and 58, one above and one below each terminal block bolt attaching perforation for the reception of wires, as 59 and 60, which are to be attached to the terminal block, as 56, or the lightning arrester.

Within each bay as between the posts 1, 2, 4 and 3, and associated with each pair of front and back panels, as 7 and 9, as shown in Fig. 4, is a wire rack or support 10, as shown in Fig. 2. This wire rack has one side composed of an angle-iron, as 61, and the other side of a reversely positioned angle-iron, as 62. One leg of the angle-iron 62 rests upon the lower leg 30 of a relay panel and a leg of the other angle-iron 61 rests upon a corresponding leg of the terminal block panel opposite.

The free legs of the angle-irons 61 and 62 are connected by rods, as 63 and 64, best shown in Fig. 3. Each of the rods is surrounded by an insulating tube, as 65 and 66. This wire rack or support 10 affords a means for suitably supporting the wires running transversely of the relay rack and passing through orifices, as 44 and 45, and also through orifices as 57 and 58, as shown in Fig. 3, to the terminal blocks as 56, as best shown in Fig. 4. By surrounding the rods, as 63 and 64, with insulating material the danger of a bare wire coming in contact with the metallic relay rack frame is largely obviated.

The construction of relay rack hereinbefore described is such that a common pedestal is provided for corner posts. These may be kept in stock and are suitable for any and all installations; standard intermediate relay panels and standard intermediate terminal block panels may be kept in stock, and are suitable for any and all installations; standard end relay panels and standard end terminal block panels may be kept in stock, and are suitable for any installation; relay and terminal block panel fastening means as U panel clamps and blades are standard, and may be kept in stock, and are suitable for any

installation; wiring templates, as 42 and 43, are standard, and may be kept, and are suitable for all installations; pinnacles, as 19 and 20, are standard, and may be kept in stock suitable for any installation; and the wire racks are of standard length and standard width so may be made in quantity, and kept in stock, and be suitable for any installation; the same is true of the lateral braces as 5 which are standard, and may be stocked without fear of loss. Practically the only variable member is the angle-iron used for corner posts, but this may be made in long lengths and be cut off at a length suitable for any particular installation so that, on the whole, very little waste would be incurred if made in stock sizes of very considerable length.

The relay rack provided by applicant is non-inflammable except for the small proportion of wiring templates, as 42 and 43, and the insulating members, as 65 and 66. It is adapted for fabrication in a shop or factory as is evident. It may be assembled in the field, as is evident, by workmen of very slight skill, by the use of no tools other than wrenches. It provides a suitable and secure panel upon which to hang a track or control relay without having that relay rest upon a base so that the danger of relay contacts closing improperly upon the breaking of the usual glass base is obviated. Each relay is positioned so as to be easily reached and inspected, and the relays and terminal blocks are all arranged so systematically that the wires going thereto may also be arranged systematically and conveniently.

Although I have particularly described one particular physical embodiment of my invention and explained the principle and operation thereof nevertheless, I desire to have it understood that the form selected is merely illustrative, but does not exhaust the possible physical embodiments of the idea of means underlying my invention.

What I claim as new and desire to secure by Letters Patent of the United States, is:

1. In a relay rack, in combination: four corner posts, arranged as at the corners of a rectangle; a relay panel, formed with a plurality of spaced orifices in a plurality of pairs, each pair adapted for the reception of means for supporting a relay, and also formed with elongated orifices, one on each side of each relay, and with an orifice at each end of each of the elongated orifices; a wiring template adapted to be secured by means passing through the orifices at each end of the elongated orifices; a terminal block panel, said terminal block panel formed with a plurality of orifices in pairs for receiving fastening means for attaching terminal blocks thereto, and with orifices adapted to receive wires for attachment to each terminal block; means for attaching the relay panel to two of the

corner posts and means for attaching the terminal block panel to the other corner posts; means securing together and spacing apart the posts supporting the relay panel with those supporting the terminal block panel; a wire supporting rack formed with two side members, one resting upon a relay panel, the other resting upon a terminal block panel, and a plurality of rods extending between the sides and attached thereto, each rod being covered with a non-conducting material in tube form.

2. In a relay rack, in combination: corner posts, each formed with a plurality of orifices; relay panels and terminal block panels, each of substantially channel form, with the ends of the legs of the channel turned in parallel with the face, each of the turned in portions being formed with notches adapted to fit partially about a bolt; U-shaped panel clamps each provided with two orifices, one positioned adjacent each end thereof, said panel clamps being of a length substantially equal to the distance between the legs of the relay and terminal block panel and being positioned between the turned over portions of the legs and the back face of the relay panels and terminal block panels; bolts, one passing through each U-shaped panel clamp orifice and through an orifice in a corner post, one U-shaped panel clamp being positioned at each end of a panel.

3. In a relay rack, in combination: four metallic corner posts arranged as at the corners of a rectangle, each corner post being formed of two angle-irons with the face of the leg of one bearing against the face of the leg of the other, and the remaining faces forming a straight line; means for maintaining the several angle-irons together, the legs forming a straight line being formed with a plurality of orifices spaced longitudinally of the corner post; means rigidly supporting and spacing adjacent the corner posts; a plurality of terminal block panels, each adapted to be attached to the corner posts at desired spacing from others and each formed with a plu-

rality of sets of a plurality of pairs of orifices adapted to receive supporting means for a relay.

4. In a relay rack, in combination: a metallic relay panel, said relay panel being substantially channel shaped in cross-section with the ends of the legs turned in and parallel to the back face, the face of the channel being formed with a plurality of sets of a plurality of pairs of orifices each adapted to receive supporting means for a relay, the panel also formed with elongated orifices, one on each side of each of the sets of orifices for receiving relay supporting means, and further formed with orifices one at each end of each of the elongated orifices; a wiring template over each of the elongated orifices and supported in place by fastening means passing through the wiring template and an orifice at each end of the elongated orifice.

5. In a relay rack, in combination: a spaced relay panel and terminal panel; a wire rack supported at one side by the relay panel and at the other side by the terminal panel, said wire rack formed with elongated sides and a plurality of rods passing therebetween, each rod surrounded by a non-conducting tube.

6. In a relay rack, in combination: a metallic corner post formed with spaced orifices vertically and horizontally; a relay panel substantially channel form in cross-section but having the ends of the legs turned in substantially parallel to the back face of the channel, said turned in portions each having a notch formed therein; a U-shaped panel clamp formed with an orifice adjacent each end thereof positioned between the legs of the channel and between the turned over portions of the legs and the back face of the channel; and bolts, one passing through each orifice in the U-shaped panel clamp, fitting into a notch in the turned over portion of the channel leg and passing through an orifice in the corner post.

FREDERICK C. LAVARACK.
